FIGURE TOY

John G. Baker, Pittsburgh, Pa.

Application February 20, 1935, Serial No. 7,372

22 Claims. (Cl. 46—134)

My invention relates to toys and particularly to figure toys.

An object of my invention is to provide a relatively simple jointed-figure toy that shall turn over and over either on a level or on an inclined surface.

Another object of my invention is to provide a figure toy that shall operate either manually or automatically as may be desired.

Other objects of my invention will either be apparent from a description of several forms of devices embodying my invention or will be pointed out during the course of the description thereof.

In practicing my invention, I provide a figure toy having a torso on which arms and legs are so mounted that either the arms or the legs or both can be moved relatively to the torso. Resilient directional means connecting two of three parts of the figure tending to yieldingly hold the arms or the legs or both extended relatively to the torso, are also provided. In the one form of device embodying my invention I connect the rounded inner ends of the arms and legs by oppositely extending or crossed initially-deformed leaf springs. In another modification I provide also an energy storing means in the hollow torso, which means may be made effective by manipulation of the toy before use thereof.

In the drawings,

Figure 1 is a view, in side elevation, of a figure toy embodying my invention and shown in three consecutive positions when in operation;

Fig. 2 is a view of the device shown in Fig. 1, also in side elevation, in three other consecutive positions during operation as a manually actuated device,

Fig. 3 is a view, in side elevation, of the device shown in Fig. 1, illustrating three different positions of the figure when operating automatically on an inclined plane surface.

Fig. 4 is a sectional view of the device shown in Fig. 1 of the drawings, taken on the line IV—IV of Fig. 1.

Fig. 5 is a view, in side elevation, of a flexible connector for two of the parts of the figure.

Fig. 6 is a view, in side elevation, with portions cut away, of a modification of the device embodying my invention.

Fig. 7 is a vertical sectional view of the device shown in Fig. 6, taken on the line VII—VII of Fig. 6.

Fig. 8 is a vertical sectional view of a modified form of device embodying my invention.

Fig. 9 is a vertical sectional view of another modification of device embodying my invention.

Fig. 10 is a vertical sectional view of still another modification of device embodying my invention, and

Fig. 11 illustrates a modification of a connecting device.

Referring to Figs. 1 and 4, I have there shown a jointed figure toy comprising a torso 11, arms 13, and legs 15. The torso is made to resemble a human body and may be made of a properly shaped piece of suitable material, such as a piece 5 of wood or other substance, such as molded compound. I provide two arms 13, one on each side of the torso, pivotally secured thereto as by means of a through pin 17, and having an end member 19 extending laterally thereacross at the outer 10 ends to represent hands. This end member is made flat and extends at substantially right angles to the arms, and may have a layer of cloth 21 or other material having a rough surface glued thereon to afford greater friction on or relatively 15 to a surface on which the toy may be operated.

The legs 15 are also pivotally mounted on the torso as by means of a pivot pin 23, and have an end piece 25 extending at right angles thereto to simulate feet. A sheet of cloth 27 may be 20 glued to the outer surface of the member 25 to increase the friction between the feet and a surface on which the toy is operated when in use. Spacing washers 28 are located between the torso and the arms and legs to reduce the area of contact 25 surface and of the friction. The inner ends of the arms and legs are rounded circularly as shown, on a radius whose center is the pivot pin.

I provide a directional, resilient means connecting two of the three parts of the figure, in the form of two leaf springs 29, shown particularly in Fig. 5 of the drawings, each of which is initially deformed to substantially the shape shown in the full lines of that figure, and each 35 of which connect an arm and a leg on one side of the figure, as shown. The position of the springs on the two sides of the figure is different in that they cross each other, the ends of the springs being connected fixedly to the edges of 40 the arm and leg by means of small screws 31. It will be noted that the initial radius of curvature of the end portions of the leaf springs 29 when free is not necessarily the same as that of the respective arcuate edge portions of the arm 45 and leg members of the figure against which they are located. This means of connecting the arms and legs of the figure ensures that all of the portions or parts of the figure will be yieldingly held in a predetermined alignment, which position may be that shown by the full lines of Fig. 1 of the drawings, that is where the figure is substantially erect, with the arms upraised.

While the springs 29 serve as an alining means for the several parts of the figure, they serve also 55 as a gear connection between the arms and legs to cause them to move in unison or to have substantially the same angular displacement relatively to the torso, but in opposite directions.

A figure of this kind can be made to somersault 60

or turn over and over on a level plane surface 33 by being pulled manually, and for this purpose I provide a bail or loop of wire 35, the inturned ends of which are fitted into small openings in the torso 11 of the figure at substantially the middle thereof, as shown in Figs. 1 and 2. When the figure is pulled by an operator, as by the use of a string tied to the bail or loop 35, on a level even plane 33, the figure will 10 turn end for end, certain sequential positions of the figure being shown in Fig. 1 in which the full lines show the position from which the figure will start when set up on its feet. In the position shown by the long and short lines, and 15 indicated by the numeral 31, the arms 13 have moved through substantially 90 degrees, while the torso 11 has moved through only one half of this angular or turning movement, or substantially 45 degrees. In the next position shown, indicated by the short lines, and designated by the 20 numeral 39, the arms have moved through an angle of substantially 180 degrees, while the torso has moved through only 90 degrees from the original position where all of three parts of the 25 figure were in substantially straight alignment and erect.

If the operator continues pulling on the bail 35, the figure will now move from the position 30 39 to the position indicated by the short lines in Fig. 2 of the drawings and designated by the numeral 41, where the hands 19 are resting on the surface 33 and the feet and legs are just beginning to raise upwardly as shown. In the next position designated by the numeral 43, the 35 feet 15 have been turned to a position such that the legs are substantially horizontal and pointing backward, it being noted that the torso has again been turned through about one half of the angular movement of the legs, that is through about 45 degrees. The next position shown in the figure is that indicated by the full lines and designated by the numeral 45, the figure now standing or resting on its hands, the legs 15 extending upwardly with the feet in the air.

45 It may be noted here that one of the springs 29, namely the one nearer the observer, was wound to a greater extent around the arcuate upper end of the leg to which it is secured and was unwound from the arcuate inner end of the 50 arm to which its upper end is connected, the opposite spring 29 having simultaneously been unwound from the rounded upper end of the leg and wound to a greater extent around the arcuate inner end (or shoulder portion) of the 55 arm to which its end is secured during the movement of the figure to the position indicated by numeral 39. That is, as the device is moved toward the right, as pulled by the bail 35, the arms 13 begin to rotate in a clockwise direction 60 around the pivot pin 17. In so doing the spring 29, nearer the observer, is unwound from or is moved out of engagement with the lower arcuate surface of the arm to which one end of it is attached and is wound upon or moved into engagement with the upper arcuate surface of 65 the leg to which the other end of it is attached. At the same time, the other spring 29, on the side opposite from the observer, is wound upon or moved into engagement with the lower arcuate surface of the arm to which one end of it is attached and is unwound from or moved out of engagement with the upper arcuate surface of the leg to which the other end of it is attached. The arms 13 then rotate at a uniform speed 70 75 around the pivot pin 17 and, at the same time,

the torso 11 rotates about the pivot pin 23 until the position 39 is reached.

In that part of the turning movement shown more particularly in Fig. 2, the near spring 29 is unwound from the leg and wound on the arm, until the lengths of surface engagement of a spring 29 and the arcuate surfaces of the arm and leg to which it is connected are again equal when the figure is standing, so to speak, on its hands. 10

The springs 29 are so designed and proportioned as to substantially counteract the effect of gravity in its attempt to lower the center of gravity of the figure. Because of this the motion of the figure as described has little resistance in 15 excess of that due to the friction of the assembly. It is difficult to balance the force of the springs and the effect of gravity in all positions of the figure, but this is no drawback in the 20 operation thereof since it results only in the speed of the turning movement being different at any given position than would be the case if exact counterbalance were present.

Referring now to Fig. 3 of the drawings, I have there shown the jointed figure toy 11 as being 25 automatically operative on a downwardly sloping plane surface 47. If the downward slope of the plane surface is sufficient the figure will fall forwardly, so to speak. The action of gravity on the jointed figure, when operating on a downwardly sloping plane surface, can be divided into two components, one component acting, as before, at right angles to the surface supporting the figure, while the other component acts parallel thereto, in the same way as the pull on the 30 string by the operator with the jointed figure located on a level surface, which need not be exactly horizontal.

When the jointed figure is operated on a level surface the operator provides sufficient force to 40 overcome the incidental frictional resistance. On the other hand when the figure is placed on a downwardly sloping surface the operation of the figure is entirely automatic. In the latter case the component of gravity acting parallel to the 45 sloping surface performs the same function as the pull of the operator in the former case.

Figs. 6 and 7 illustrate a figure toy that is automatic in that it will flip over on a level plane surface. The jointed figure comprises a hollow torso 50 51, arms 53, hands 55, legs 57, and feet 59,—the arms, hands, legs and feet being substantially the same as were hereinbefore described for the device shown in Figs. 1, 2, and 3. The torso 51 may comprise a main portion 61 having a circular 55 recess 63 therein and a cover plate 65. The arms 53 are each pivotally mounted on the torso by pivot pins 61, which are so designed and mounted as to remain fixed in the torso. The legs are also pivotally secured to the torso as by pivot pins 69 and 60 the same precautions are taken to preclude accidental dropping out of the pivot pins. Of course the pivot pins for the arms and legs may be fixed or secured in the arms and legs respectively instead of the torso. A facing sheet 71, of rough 65 material, may be located on the hands and on the feet respectively to increase the friction thereof relatively to the plane surface on which the toy operates, although I have found this is not a necessity. 70

Centrally of the substantially circular opening 63 there is located a loose shaft 73 having secured thereto adjacent one end thereof one end of an arm 75, to the other end of which is secured a weight 77, which as shown particularly in Fig. 6 75

is in the form of a segment of a circle to obtain the maximum weight in a relatively small volume at a distance as great as possible from the axis of suspension of the weight. A helical spring 79 surrounds the shaft 73 and has one end thereof interfitting with the torso and the other end thereof interfitting with the arm 75. In order to ensure that the weight 77 and the arm 75 will turn freely with or on the shaft 73, I may provide a spacing washer 81 between the shaft end of arm 75 and the cover plate 65.

Springs 83 of the same design as the springs 29 are provided to connect the arm and leg on one side of the torso, two such springs being provided in substantially the same manner as heretofore described.

The figure toy shown in Figs. 6 and 7 is operated in the following manner: as the figure is desired to move forwardly the spring 79 is wound up by an operator grasping the entire figure and giving it a rotational motion in a clockwise direction until the spring has been wound up as much as can be done, by causing the weight to move around the shaft 73. The player now sets the figure down on a level even plane and the wound-up spring 79 tends to move the weight in a counter clockwise direction, which tends to unbalance the figure and cause it to fall or move forwardly on its feet and legs. Or to put it in other words, since the spring has one of its ends connected pivotally to the torso, the torso will be caused to turn in a clockwise direction on the pivot pins 69. The figure will operate automatically in substantially the same manner as was hereinbefore described for the form of device illustrated in Figs. 1, 2, and 3, the turning movement continuing until the spring 79 has been substantially completely unwound.

A spring drive suitable for operating a figure toy of the kind herein described is disclosed and claimed in my copending application Serial No. 7,373 entitled Spring drive and filed as of even date herewith.

Referring now to Fig. 8 of the drawings, I have there illustrated a modified form of device embodying my invention, based more particularly on the device shown in Figs. 1, 2, and 3. A substantially solid body or torso 91 has pivotally mounted thereon a pair of arms 93, having hands 95 secured thereto, legs 97 with feet 99 thereon, the hands and feet having an outer rough surface 101 thereon as has already been described. Pivot pins 103 and 105 mount the arms and legs respectively on the torso. Straps or strips 107 of flexible but inextensible material are provided to connect the respective arm and leg on each side of the figure as already described, and may be said to gear the respective arms and legs together. The directional alining force is supplied by a spiral spring 109, which has one end connected to one leg, and its other end connected to the torso as by a pin 111. Spacer plates and washers 113 and 115 are provided as has already been set forth in connection with the device shown in Figs. 1, 2, and 3.

The spiral spring 109 provides the desired directional force to hold the three parts of the figure in predetermined alinement, which in the case of a device simulating the human figure is that shown where the arms, legs and the torso are in substantial straight alinement.

Another modification of the device embodying my invention is shown in Fig. 9 of the drawings, and which differs from those already described by the use of a directional element in the shape of a helical spring 117 whose ends are connected to

small screw eyes 119 screwed into an arm and a leg respectively on one side of the figure, with a small initial tension. In all other details it is the same as that shown in Fig. 8.

Fig. 10 of the drawings shows still another modification of device embodying my invention, the three parts of the figure being substantially the same as that shown in Fig. 8 with the exception that the directional force is provided by a small helical spring 121 whose ends are connected respectively to the bottom end of the torso and to the feet by means of small screw eyes 123.

It is to be noted that the spring members 29 of Figs. 1, 2, and 3, 83 of Figs. 6 and 7, 109 of Fig. 8, 117 of Fig. 9, and 121 of Fig. 10 tend to 15 yieldingly hold the three parts of the associated figure in predetermined alinement cooperating, of course, with the straps or strips connecting the arms and legs in pairs as set forth. The spring 109 of Fig. 8 can be so located as to connect the 20 torso and the arms, that is, the spring 109 will surround the pivot pin 103. The devices shown in Figs. 8, 9, and 10 will operate in the same manner as has already been set forth in connection with the device shown in Figs. 1, 2, and 3, on 25 either a level even surface or on a downwardly sloping surface.

It is to be noted also that any other equivalent connecting means for the respective arm and leg members on the two sides of the figure may be 30 used instead of the straps or strips as shown, and I have shown this generally in Fig. 11 of the drawings where an arm 125 and a leg 127 are shown in proper cooperative positions and as being provided with meshing teeth 129 and 131 respectively. Where the figure is made of wood I find it desirable to use the strap connections between the arm and leg members but in case of thin metal figures it may be desirable to use teeth as shown in this figure of the drawings.

It is obvious that the device embodying my invention provides a relatively simple figure toy comprising a small number of component parts so connected that it is possible to operate the figure either on a level surface by an external pull 45 or on an inclined surface, or in a modification of the device, it can be operated by power stored therein by a player or operator.

While I have illustrated and described several modifications of a device embodying my invention, I do not desire to be limited thereto, the invention in its broadest aspect being set forth in the appended claims.

I claim as my invention:—

1. A figure toy comprising a torso, arms and 55 legs movably mounted on the torso and means operatively associated with the arms and legs for insuring that the angular displacement of the legs relatively to the torso shall be substantially equal and opposite to that of the arms.

2. A device as set forth in claim 1 in which the means operatively associated with the arms and legs comprises crossed strips of resilient inextensible material.

3. A figure toy comprising a torso and arms 65 and legs movably mounted on the torso and resilient means connecting two of the parts of the figure to yieldingly hold the three parts of the figure in predetermined alinement.

4. A figure toy comprising a torso, arms and 70 legs, means pivotally mounting the arms and legs on the torso and resilient means extending between and connecting two of said parts of the figure to yieldingly hold the three parts of the figure in substantial alinement.

5. A figure toy comprising a torso, arms and legs, means pivotally mounting the arms and legs on the torso, and springs connecting the arms and the legs and effective to yieldingly hold the three parts of the figure in alinement and to insure equal and opposite angular movement of the arms and legs.
6. A figure toy comprising a torso, arms and legs, means pivotally mounting the arms and legs on the torso, and initially deformed leaf springs connecting the arms and legs and effective to hold the three parts of the figure in alinement.
7. A figure toy comprising a torso, arms and legs, means pivotally mounting the arms and legs on the torso, and a pair of oppositely-extending initially deformed springs each connecting an arm and a leg to hold the three parts of the figure normally in predetermined alinement.
8. A figure toy comprising a torso, arms and legs, means pivotally mounting the arms and legs on the torso, flexible means connecting the arms and legs and resilient means extending between and connecting two parts of the figure to yieldingly hold the three parts in alinement.
9. A figure toy comprising a central part and two end parts extending radially from the central part, means pivotally mounting the end parts on the central part, and means operatively connecting two of said parts of the figure to effect substantially twice the angular movement of one end part relatively to the angular movement of the central part while the other end part remains stationary.
10. A figure toy comprising a torso, arms and legs mounted on the torso, resilient directional means extending between and connecting two parts of the figure to yieldingly hold all the parts in predetermined alinement, an energy storing means in the torso and means operatively connecting said energy storing means to the torso.
11. A figure toy comprising a torso, arms and legs pivotally mounted on the torso, resilient directional means extending between and connecting two parts of the figure to yieldingly hold all the parts of the figure in predetermined alinement, an energy storing means in the torso including a spring and a weight operatively associated with each other and with the torso to cause motion of the figure.
12. A figure toy comprising a torso, arms and legs pivotally mounted on the torso, resilient directional means extending between and connecting two parts of the figure to yieldingly hold all the parts of the figure in predetermined alinement, an energy storing means in the torso including a helical spring having one end fixed in the torso and a weight located eccentric to the spring and engaged by the other end thereof.
13. A figure toy comprising a hollow torso having a substantially central shaft therein, and arms and legs pivotally mounted on the torso, resilient directional means extending between and connecting two of the parts of the figure to yieldingly hold all the parts in predetermined alinement, a weight in the torso located eccentric to the shaft and pivotally mounted on the shaft and a helical spring surrounding the shaft and having one end fixed in the torso and the other end operatively connected to the weight.
14. A figure toy comprising a hollow torso having a substantially central shaft therein, and arms and legs pivotally mounted on the torso, directional means including a pair of crossed initially deformed leaf springs having their ends secured to the respective pair of arms and legs to yieldingly hold all of the parts of the figure in predetermined alinement, a weight in the torso eccentric to the shaft and pivotally mounted on the shaft and a helical spring surrounding the shaft and having one end fixed in the torso and the other end operatively connected to the weight.
15. A figure toy comprising a torso, arms and legs movably mounted on the torso, means operatively associated with the arms and the legs to ensure that the angular displacement of the legs relative to the torso shall be substantially equal and opposite to that of the arms and means for yieldingly holding arms, legs and torso in predetermined alinement.
16. A figure toy comprising a torso, arms and legs movably mounted on the torso, means operatively associated with the arms and legs to ensure that the angular displacement of the legs relative to the torso shall be substantially equal and opposite to that of the arms, means for yieldingly holding the arms, legs and torso in predetermined alinement, means for storing elastic energy in the figure and means to release the elastic energy to cause the toy to turn over and over.
17. A device as set forth in claim 16 in which the means for ensuring an angular displacement of the legs equal and opposite to that of the arms is combined with means for holding the arms, legs and torso in resilient yielding alinement in the form of crossed springs of resilient material connecting arms and legs together.
18. A figure toy comprising a torso, arms and legs, said arms and legs being pivotally mounted on said torso, and spring means interconnecting said arms and legs and tending to hold the three parts of the toy in predetermined relation and causing successive angular movement of said arms and legs.
19. A figure toy comprising a torso, arm and leg members pivotally mounted on said torso, and initially deformed leaf spring means interconnecting said members for effecting successive angular displacements thereof relative to said torso.
20. A figure toy comprising a body member, arm and leg members movably mounted on said body member, means operatively associated with said arm and leg members to ensure that the angular displacement of the leg member relative to said body member shall be substantially equal and opposite to that of the arm member, and means for resiliently holding said arm, leg and body members in predetermined relationship.
21. A figure toy comprising a torso, arms and legs movably mounted on the torso, and means operatively associated with the arms and legs for ensuring that the angular displacement of the legs relatively to the torso shall be substantially equal and opposite to that of the arms and tending to relatively move said arms, legs and torso out of a predetermined relationship.
22. A figure toy comprising a body member, arm and leg members movably mounted on said body member, and means operatively associated with said arm and leg members for ensuring that the angular displacement of said arm and leg members relative to said torso shall be substantially equal and opposite and for biasing said arm, leg, and body members toward a predetermined relationship.

JOHN G. BAKER.
